UNITED STATES PATENT OFFICE.

GEORGE BARTON MULLEN, OF NEW YORK, N. Y.

SANITARY COVER FOR TELEPHONE MOUTHPIECES.

Application filed April 8, 1925. Serial No. 21,616.

To all whom it may concern:

Be it known that I, GEORGE B. MULLEN, a citizen of the United States, and a resident of the city of New York, borough of Queens, 5 Bayside, in the county of Queens and State of New York, have invented a new and Improved Sanitary Cover for Telephone Mouthpieces, of which the following is a full, clear, and exact description.

10 This invention relates to a sanitary cover for telephone mouthpieces.

An object of the invention is to provide a simple and efficient device that can be dispensed on the market in a manner similar 15 to the ordinary paper cups that are now sold, so that each person desiring to use the telephone can get a cover and easily slip it over the mouthpiece of the telephone so as to prevent the collection of germs on the 20 mouthpiece, rendering the same unsanitary and liable to transmit disease germs to others using the telephone.

The invention is illustrated in the drawings, of which—

25 Figure 1 shows the side elevation of the telephone with the mouthpiece partially in section with the cover attached; and

Figure 2 is a plan view of the cover.

The form of the invention shown in the 30 drawings is a preferred form, although it is understood that modifications in the construction and arrangement of the parts and in the character of the materials used may

be adopted without departing from the spirit of the invention as set forth in the 35 appended claim.

The preferred form of the invention is adapted to be applied to a telephone 10 having a mouthpiece 11. Over this mouthpiece a sheet 12 is adapted to be disposed. This 40 sheet has its edges bent over as at 13 to form flanges adapted to engage the edge of the mouthpiece to hold the cover thereon.

Preferably this sheet of material is made of loosely woven fabric, such as cheesecloth, 45 gauze, etc. This material may be stiffened by treating it with size, by reinforcing with wires woven thereinto, in any other suitable manner. The material, preferably, is also treated with some suitable chemical 50 agent acting as an antiseptic. It may also be preferable that the chemical give out a pleasant odor to counteract the disagreeable odor of the disinfectant or antiseptic medium. 55

What I claim is:—

A sanitary cover for a telephone mouthpiece which comprises a flat circular sheet of loosely woven material impregnated with an antiseptic substance and disposed across 60 the mouthpiece of the telephone transmitter, the edges of the sheet being stiff and bent over the edge of the mouthpiece to hold the cover thereon.

GEORGE BARTON MULLEN.
